UNITED STATES PATENT OFFICE.

WALTER S. STAIRS, OF PHILADELPHIA, PENNSYLVANIA, ASSIGNOR TO MARSHALL FIELD MILLS CORPORATION, OF PHILADELPHIA, PENNSYLVANIA, A CORPORATION OF PENNSYLVANIA.

WOVEN PILE FABRIC.

Application filed October 28, 1925. Serial No. 65,298.

This invention relates to improvements in woven pile fabrics of the "Wilton" class wherein sets of pile threads are floated in lapping relation between upper and lower 5 weft strands or threads and extended upwardly at certain intervals between adjacent upper weft strands to form the pile of the fabric, the pile threads being confined between the upper and lower weft strands, 10 and the weft strands being bound into the fabric by binding warp threads.

The invention aims to cheapen the cost of production of fabrics of this class and to provide a novel fabric structure which can 15 be produced in less time than heretofore and which will be strong and durable when in service.

The desired aim is accomplished by interweaving a continuous thread forming the 20 weft strands with the pile threads and binding warp threads in a novel manner, as will be hereinafter explained; and the invention consists of the elements and the combinations of them hereinafter described and particularly claimed.

In the accompanying drawings illustrating the invention:

Figure 1 is a side view of a pile fabric embodying my invention, as seen from one 30 of the lateral edge portions thereof.

Figure 2 is a side view of the fabric as seen from the opposite lateral edge portion thereof.

Figure 3 is a longitudinal section through 35 the fabric, on line 3—3 of Fig. 1.

Figure 4 is a transverse section through the fabric, on line 4—4 of Fig. 3.

Referring to the drawings, 2 designates 40 pairs of binding warp threads, 5 sets of pile threads, and 6 a continuous thread which forms upper and lower pairs of weft strands 7 and 8, respectively.

The pairs of binding warp threads 2 are arranged at spaced intervals throughout 45 the width of the fabric and the sets of pile threads 5 alternate with the pairs of binding warp threads 2 and are arranged between next adjacent pairs thereof, as clearly shown in Fig. 4, and they extend longitudinally of the fabric or in the general direction of the warp threads 2. Any desired or suitable number of pile threads may be employed in each set 5 thereof, six threads

being shown in the drawings in each set for convenience of illustration. 55

The upper and lower pairs of weft strands 7 and 8 extend transversely of the fabric from side to side thereof above and below the sets of pile threads 5, respectively; and the threads of the pairs of binding warp threads 2 pass above and below the upper and lower pairs of weft strands 7 and 8 and cross each other within the body of the fabric, as shown in the drawings, and thereby bind the pairs of weft strands 7 and 8 into the fabric and cause them to bind the sets of pile threads 5 into the fabric. 60 65

The pile threads of the sets thereof are floated side by side longitudinally through the body of the fabric between upper and lower pairs of weft strands 7 and 8 and between laterally adjacent pairs of binding warp threads 2; and, at certain regular intervals throughout the length of the fabric one thread of each set is extended upwardly 70 75 between adjacent upper pairs of weft strands 7 to form the pile 9 which may be cut, as herein illustrated, or which may remain uncut, as desired. Thus, by employing different colors in the pile threads of the several sets 5 thereof, different designs may be produced in the fabric, the threads of the several sets 5 being floated between the pairs of weft strands 7 and 8 when not appearing upon the upper surface of 80 85 the fabric in the form of the pile 9.

At the lateral edge portion of the fabric shown in Fig. 1, the weft strands of the upper pairs 7 thereof are connected to the weft strands of the lower pairs 8 thereof by 90 loop portions 10 and 11 which are formed by the continuous thread 6, so that the continuous thread extends around the sets of pile threads 5 in connecting the upper and lower pairs of weft strands 7 and 8 at one 95 lateral edge of the fabric and thereby prevents the pairs of weft strands from being withdrawn from between the binding warp threads 2 and the pile threads 5 or displaced longitudinally in the fabric in the direction 100 of the arrow 12 in Fig. 4 or toward the edge portion of the fabric shown in Fig. 2. The portions 11 of the continuous thread 6 extend only around the floated portions of the pile threads 5, and the portions 10 also extend around the crossed pairs of binding 105

warp threads 2, as shown in Fig. 1, which further prevents such withdrawal or longitudinal displacement of the pairs of weft strands 7 and 8.

5 At the lateral edge portion of the fabric shown in Fig. 2 there is provided a supplemental binding thread 13 which extends longitudinally of the fabric or in the general direction of the binding warp threads 2 and 10 pile threads 5; and the upper and lower pairs of weft strands 7 and 8 are connected to this supplemental thread 13 by loops 14 and 15 formed by the continuous thread 6 and forming extensions of the pairs of weft 15 strands 7 and 8 and extending around or embracing the thread 13, as shown in Figs. 2 and 4. Thus, the supplemental binding thread 13 prevents the pairs of weft strands 7 and 8 from being withdrawn from between 20 the binding warp threads 2 and the pile threads 5 or displaced longitudinally in the fabric in the direction of the arrow 16 in Fig. 4 or toward the edge portion of the fabric shown in Fig. 1.

25 The course of the continuous thread 6 through the fabric is as follows: From the point 17 shown in Fig. 1, it extends above the sets of pile threads 5 from the edge of the fabric shown in Fig. 1 to the edge shown in Fig. 2. It then forms a loop 14 around the supplemental binding thread 13 and extends back above the sets of pile threads 5 to the edge of the fabric shown in Fig. 1. It then extends around the sets of pile 30 threads 5 to the bottom thereof and forms a loop 10 from which it extends beneath the sets of pile threads 5 to the edge of the fabric shown in Fig. 2 and there forms a loop 15 around the supplemental binding 35 thread 13, and from this loop 15 it extends back beneath the sets of pile threads 5 to the edge of the fabric shown in Fig. 1. It then extends around the sets of pile threads 5 and around the crossed adjacent threads of 40 the pairs of binding warp threads 2 to the top of the pile threads 5 and forms a loop 11 from the top of which its course just described is repeated throughout the fabric.

45 If desired, a filling thread 18 may be interposed between the loop portions 10 and 11 and the next adjacent pair of binding warp threads 2 at the edge portion of the fabric shown in Fig. 1.

I claim as my invention:—

50 1. A woven pile fabric comprising pairs of binding warp threads alternating with

sets of pile threads extending in the direction of the binding threads, and a continuous thread passing under and over the pile threads and around the same at one lateral 60 edge portion of the fabric and forming pairs of weft strands above and below the pile threads, a supplemental binding thread extending in the direction of the warp threads at the other lateral edge portion of the fabric, each pair of upper and lower weft strands forming a loop which embraces said supplemental thread, the upper and lower pairs of weft strands confining the sets of pile threads between them and being bound 65 into the fabric by the pairs of binding warp threads, and the pile threads of each set thereof extending upwardly between adjacent upper pairs of weft strands at certain 70 intervals and forming pile and being floated side by side in lapping relation between the upper and lower pairs of weft strands and between laterally adjacent pairs of binding warp threads when not forming pile.

75 2. A woven pile fabric comprising pairs 80 of binding warp threads alternating with sets of pile threads extending in the direction of the binding threads, and a continuous thread passing under and over the pile threads and forming pairs of weft strands 85 above and below the same, the continuous thread passing around the pile threads at one edge portion of the fabric at certain intervals and around pairs of binding warp threads at the same edge portion of the fabric at certain intervals, a supplemental binding thread extending in the direction of the warp threads at the other lateral edge portion of the fabric, each pair of upper and lower weft strands forming a loop which 90 embraces said supplemental thread, the upper and lower pairs of weft strands confining the sets of pile threads between them and being bound into the fabric by the pairs of binding warp threads, and the pile threads of each set thereof extending upwardly between adjacent upper pairs of weft strands at certain intervals and forming 95 pile and being floated side by side in lapping relation between the upper and lower pairs of weft strands and between laterally adjacent pairs of binding warp threads when not forming pile.

100 In testimony whereof I affix my signature.

WALTER S. STAIRS.
